CLAIM

The ornamental design for an under-seat storage compartment, as shown and described.

DESCRIPTION

FIG. 1 is a perspective view of a under-seat storage compartment attached to a folding stadium-type seat shown in phantom is for illustrative purposes only and forms no part of the claimed design.

FIG. 2 is another perspective view thereof.

FIG. 3 is bottom view thereof.

FIG. 4 is front view thereof.

FIG. 5 is right side view thereof, a left side being identical thereto.

FIG. 6 is a top view thereof; and,

FIG. 7 is a rear view thereof.
